[57] CLAIM

The ornamental design for an adaptor for light switches, as shown and described.

DESCRIPTION

FIG. 1 is a right side elevational view of an adaptor for light switches showing my new design, the left side being a mirror image thereof;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a top, rear and right side perspective view thereof illustrating my new design in use, the broken lines showing of a light switch and cover are for illustrative purposes only and form no part of the claimed design.
